UNITED STATES PATENT OFFICE.

JOHN P. COMER, OF CLEVELAND, OHIO.

SHOE-STRETCHING MACHINE.

Application filed January 23, 1922. Serial No. 531,011.

To all whom it may concern:

Be it known that I, JOHN P. COMER, a citizen of the United States, residing at Cleveland, in the county of Cuyahoga and State of Ohio, have invented a certain new and useful Improvement in a Shoe-Stretching Machine, of which the following is a full, clear, and exact description, reference being had to the accompanying drawings.

10 This invention pertains to improvements in shoe machines, and is particularly concerned with shoe stretching machines.

15 The general object of my invention is the provision of a shoe leather stretching machine adapted to act upon any selected zone of the shoe leather surface in effecting the stretching of that zone by the action of cooperating rollers disposed interiorly and exteriorly of the shoe.

20 Another object of my invention is the provision of a small, compact, durable machine wherein means are provided for rolling the surfaces of the shoe leather under pressure, whereby the fibres of the leather are relatively displaced, to bring about a local stretching of the leather.

25 Other objects will be hereinafter set forth in the following description given in connection with the accompanying drawings. The 30 essential characteristics will be summarized in the claims.

35 In the drawings, Fig. 1 is a side elevation of a machine embodying my invention; Fig. 2 is a front elevation of the machine; while Fig. 3 is a cross sectional view illustrating the result obtained by subjecting a portion of the shoe leather to the stretching action of my device.

40 In carrying out the purpose of my invention I have provided a machine wherein a pair of rollers are arranged to act under pressure upon the shoe leather in such a manner as to squeeze the fibres of the leather and cause a relative displacement thereof. 45 This rolling or kneading of the leather being such as to replace the expedient heretofore resorted to which required the use of a stretching frame expanded interiorly of the shoe and upon which the leather was repeatedly pounded with a mallet.

50 A preferred form of my invention is illustrated in Fig. 1, wherein a standard 5, having an integral base 6, and an overhanging arm 7 is arranged to support an arbor 8 in an integral bearing 9 formed intermediate of the overhanging arm 7 and the base 6. The

arbor 8 is provided with an upwardly extending U-shaped portion 8^a which affords a grip for the hand in rocking the arbor as well as a clearance for the counter of the 60 shoe.

The arbor may have a counter weight 10 secured to the outer end thereof, a portion of which also serves as a collar to properly maintain the arbor in position on the standard 5. Any suitable means, such as a nut 11 may serve to maintain the counter weight 10 on the outer end of the arbor.

65 The arbor is provided with a roller member 12 which is suitably mounted upon the 70 end thereof. A second roller 13 is supported upon a pressure plunger 14 which is slidably supported in a suitably formed bearing portion 7^a of the arm 7, and depends therefrom. An elevating lever 15 is swivelly 75 mounted on the upper end of the member 14 and serves to raise the stem 14, and consequently the roller 13 away from the roller 12, when it is desired to place a shoe in the machine.

80 A heavy spring member 16 may be disposed between the under surface of the bearing portion of the arm 7 and a collar member 17 which is adjustably mounted on the lower portion of the stem 14. The collar 85 member 17 may be adjusted along the stem 14 to vary the compression of the spring 16. The roller 13 is rigidly positioned on a shaft 18 which is suitably mounted between the 90 yoke portions 14^a of the stem 14.

95 The shaft 18 has an enlarged extension 18^a which is suitably milled or knurled to afford firm gripping thereof by the fingers, whence the roll 13 may be turned or oscillated by the twisting or turning of the handle portion 18^b.

100 If it is desired to maintain the rollers with their axes in parallelism, any suitable means, such as a screw member 20 may be arranged to engage the stem 14 in a suitable slideway 21 formed in the upper portion thereof.

105 The operation of the device is as follows: The cam lever 15 is turned to a vertical position in alignment with the plunger member 14, as illustrated in Fig. 2, thus drawing the plunger 14 upwardly and further compressing the spring member 16 between the arm 7 and the collar 17. This camming or elevating action is sufficient to raise the roll 13 a suitable distance away from the roll 12, whence sufficient space is obtained between the rolls to permit the mounting of a shoe.

upon the roll 12 and the arbor 8. The lever 15 may then be shifted to lower the plunger 14 under pressure of the spring 16, and the roller 13 consequently will press or pinch the shoe leather against the roll 12.

The shoe may be shifted inwardly or outwardly on the arbor 8 until the zone of the leather surface, which it is desired to stretch, is positioned between the rollers. 10 The leather may then be squeezed or pressed by a turning of the roll 13 through the finger portion 18 of the shaft member 18, upon which the roll 13 is rigidly mounted. This causes the shoe leather to be passed back and forth between the rolls and eventually results in a squeezing and displacing of the fibres which increases the area of the leather surface which is being rolled and an effect is produced such as is substantially illustrated 15 in Fig. 3.

It will be noted that the central portion 22 of the stretched section of the leather is thinner than the surrounding contiguous portions of leather 23. This distortion of 25 the leather through the displacing of the fibres is readily and rapidly obtained without injuring the general fibre structure of the portions of the leather being stretched.

The arrangement of the various parts of 30 my device while being of the simplest design, nevertheless are such that a small, compact, stretching tool is provided which will effectively produce a stretching of any desired portion of the leather in the shoe up- 35 per.

Another advantage to be attained by the use of my invention is the elimination of the bruised or marred appearance of the stretched leather surface which has heretofore resulted when the exterior surface of 40 light shoes, such, for instance, as tan or brown, has been struck with a mallet. Such treatment usually resulted in a discolouration of the surfaces of the stretched portions 45 of the shoe, which discolouration I prevent by rolling or ironing the leather.

Having thus described my invention, I claim:

1. In a device of the character described, 50 the combination of a pair of rolls for compressively acting on any portion of the leather in a shoe upper, and means for supporting said rolls in yieldable relation, including means for supporting one of the rolls 55 interiorly of a shoe.

2. In a device of the character described, 60 the combination of a pair of leather pressing rolls, means for supporting one of the rolls exteriorly of a shoe, and means for supporting the other of said rolls interiorly of the shoe and in juxtaposition to said first named roll.

3. In a device of the character described, 65 the combination of a pair of rolls adapted to exert pressure interiorly and exteriorly on

selected portions of the leather in a shoe upper, means for supporting the shoe including means for supporting one of said rolls interiorly of the shoe, and means for supporting the other of said rolls in a compressive relation to the first named roll. 70

4. In a device of the character described, the combination of a pair of rolls adapted to exert pressure interiorly and exteriorly on 75 selected portions of the leather in a shoe upper, means for supporting one of said rolls interiorly of the shoe, and means for rotatably supporting the other of said rolls in juxtaposition to the first named roll.

5. In a device of the character described, 80 the combination of a plurality of rolls adapted to exert pressure on the leather in the upper part of a shoe, means for supporting one of the rolls interiorly of the shoe, and means for yieldably supporting the other of said rolls 85 exteriorly of the shoe and in compressive relation to said first named roll.

6. In a device of the character described, the combination of a plurality of rolls adapted to exert pressure on the leather in the 90 upper part of a shoe, means for supporting one of the rolls interiorly of the shoe including means for supporting the shoe, and means for yieldably supporting the other of said rolls exteriorly of the shoe and in compressive relation to said first named roll. 95

7. In a device of the character described, the combination of a pair of rolls, movable means supporting one of the rolls, and means for supporting the other of said rolls 100 interiorly of the shoe whence the first named roll may be moved into juxtaposition to the second named roll and exert pressure upon the exterior surface of an intervening portion of the shoe leather, while the other of 105 said rolls may exert pressure on the inner surface of said shoe leather.

8. In a device of the character described, a pair of rolls, one of which is adapted to 110 be disposed interiorly of a shoe and serve to support a portion of the shoe leather, while the other of said rolls exerts pressure on the exterior surface of the shoe leather during a rotatable movement thereof. 115

9. In a device of the character described, 115 a pair of leather stretching rolls, one of which is adapted to be disposed interiorly of a shoe and serve to act on the interior surface of the shoe leather, while the other of said rolls acts on the exterior surface of the 120 shoe leather to displace the fibres of the leather and consequently increase the area of the leather surfaces being acted upon.

10. In a device of the character described, 125 the combination of a pair of rolls, means for supporting one of the rolls interiorly of a shoe, means for pressing the other of said rolls on the exterior surface of said shoe and in juxtaposition to said first named roll, and means for rotating the exteriorly disposed 130

roll whereby the fibres of the shoe leather passing between said rolls will be relatively displaced and the leather stretched in consequence thereof.

5 11. In a shoe stretching machine, a pair of leather stretching rolls, one disposed interiorly of the shoe and the other resiliently supported exteriorly of the shoe in juxtaposition to said first named roll by movable 10 means tending to decrease the space between said rolls.

12. In a shoe stretching machine, the combination of a pair of rolls having their axes relatively movable, means for supporting 15 one of said rolls interiorly of the shoe including a shoe support having an offset portion affording clearance for the shoe counter, and means for shifting the rolls toward and away from each other.

20 13. In a shoe stretching machine, the combination of a pair of relatively movable pressure rolls, means for supporting one of the rolls interiorly of the shoe, and means tending to decrease the distance between 25 said rolls when acting on the shoe including an arm rigid with the base of the device, and a relatively movable member upon which the other of said rolls is mounted.

14. In a shoe stretching machine, the combination of a pair of relatively movable 30 rolls, means for supporting one of said rolls interiorly of the shoe including a shoe support having an offset portion affording clearance for the shoe counter, and a stand-

ard, said shoe support being removably 35 mounted on said standard.

15. In a shoe stretching machine, a pair of stretching rolls, one supported interiorly of the shoe and the other supported exteriorly of the shoe and in juxtaposition to said 40 first named roll on movable means associated with resilient means tending to decrease the space between said rolls.

16. In a shoe stretching machine, the combination of a pair of rolls one being arranged 45 to lie supported interiorly of the shoe by shoe supporting means, the other of said rolls being supported exteriorly of the shoe by movable means, a standard upon which said shoe supporting means and said roll 50 moving means are supported, and resilient means reacting on the standard and exerting pressure on said last named means.

17. In a shoe stretching machine, the combination of a pair of rolls one arranged to 55 lie disposed interiorly of the shoe, while the other may be disposed exteriorly of the shoe and in juxtaposition to said first-named roll, means for rigidly supporting said interiorly disposed roll, a spindle supporting the exteriorly disposed roll, and a spring therefor acting upon the spindle and means for adjustably varying the pressure exerted by said spring on said roll.

In testimony whereof, I hereunto affix my 65 signature.

JOHN P. COMER.
